UNITED STATES PATENT OFFICE.

ARTHUR A. OSWALD, OF EAST ORANGE, NEW JERSEY, ASSIGNOR TO WESTERN ELECTRIC COMPANY, INCORPORATED, OF NEW YORK, N. Y., A CORPORATION OF NEW YORK.

PORTABLE RADIATING SYSTEM.

1,418,729.

Specification of Letters Patent. Patented June 6, 1922.

Application filed April 25, 1919. Serial No. 292,691.

To all whom it may concern:

Be it known that I, ARTHUR A. OSWALD, a citizen of the United States, residing at East Orange, in the county of Essex, State of New Jersey, have invented certain new and useful Improvements in Portable Radiating Systems, of which the following is a full, clear, concise, and exact description.

This invention relates to a radiating system for use on a moving vehicle and has particular reference to antennæ for aerial vessels such as aeroplanes and the like. A feature of the invention relates to the connection of trailing wires to the aeroplane or the like in a manner that is mechanically adapted to the structure and motion of the machine and at the same time is electrically efficient for radiating and receiving energy.

Heretofore it has been the practice to use a single trailing wire as an antenna for an aeroplane. The wire is wound on a reel and is released as desired while the machine is in flight. To secure the necessary electrical properties the wire has to have a considerable length and to aid in unreeling the wire and for causing it to trail properly a weight is attached at the end. The reel is conveniently mounted within reach of the operator, which means that the trailing wire is in such position as to be liable to come into contact with some part of the aeroplane if any complicated manoeuvring of the machine is attempted. Such contact might endanger the machine either from the mechanical or electrical effects, such as by becoming entangled with the machine or causing sparks to pass between the wire and the conducting portions of the machine. This type of antenna is especially unsuited for use where several machines are operating together as, for instance, in squadron formation, both on account of the great length of the wire and the presence of the weight, and because the machine must be free to execute complicated movements. In addition the single trailing wire has a very marked directional property which is not always desirable.

To overcome these faults a pair of trailing wires attached near the extremities of the wings have been advocated, one wire being used as antenna against the other as a counterpoise. These wires are of small gauge, are unweighted and no reel is provided for them, but they are permitted to trail when

the machine is either on the ground or in the air and their mounting on the wings leaves them clear of the machine, so that they do not interfere with its movements.

However the electrical properties of two such wires when one was used as an antenna against the other as counterpoise, were found to be unsatisfactory for practical operation. This type of antenna was found incapable of any practical communication with a ground station, either for receiving or sending. Among other defects noted, large losses were found to occur, probably being dielectric losses or absorption due to the capacity effects of the wires and their necessary connecting leads relative to the metallic frame of the machine.

According to the present invention the two wires attached to the extremities of the wings or transverse portion of the aeroplane, are connected in parallel as an antenna against the metallic framework of the machine as a counterpoise. This method of connection alone was found to give the desired directional effect for communicating with a ground station, but the energy losses were still found to be very large. According to a further feature of the invention, the trailing wires and the leading-in wires are given a considerable spacing relative to every part of the metallic framework of the machine by properly proportioned insulating supporting means, and the capacity of the wires relative to the frame structure is thereby reduced. With this provision the energy losses are reduced to a negligible value. This form not only maintains the desired mechanical characteristics of the two trailing wires but has proven in practice to have satisfactory operating characteristics as a radiating and receiving antenna, the directional property of the antenna being less marked than in the case where a single trailing wire is used.

In the drawing, Fig. 1 is a plan view of an aeroplane equipped with an antenna according to the invention, and Fig. 2 is a side elevation of Fig. 1.

The trailing wires 1 and 2 are each connected to the leading-in wire 3 as indicated at points 4 and 5. The length of the trailing wires may be varied according to the wave-length to be used. In practice the length has actually been varied between about thirty feet and one hundred and fifty

feet. A supporting and insulating means 6 is shown for mechanically attaching the wires 1, 2 and 3 to the struts 7 of the aeroplane shown. The means 6 may conveniently be cords of non-conducting material and in practice may be several feet in length. Other supporting means 8 similar to the means 6 may be provided. Rigid supporting arms 9 are shown near the center of the leading-in wire 3 and the connection to the radio sets (which are not shown but which would generally be in the fuselage 10) may conveniently be made from the portion of wire 3 included between supports 9 as indicated at 11. The "ground" connection of the radio sets is connected to the metal framework and other metal parts of the machine, some of which are shown at 12, which are preferably electrically connected together to serve as counterpoise. Instead of the flexible supporting means 6 rigid insulating means could, of course, be employed. The arrangement of connection may also be varied in other respects, according to the conditions of use.

It is to be understood that the numerical values given are for illustrative purposes only and that the invention is not to be limited thereby. Also the invention is not limited to use on an aeroplane but might be used on other types of moving vehicles. Nor is the invention to be limited in other respects by the showing, but only by the scope of the appended claims.

What is claimed is:

1. An antenna for an aeroplane or the like having a metallic structure, said antenna comprising a plurality of trailing wires sup-

ported from the outer portions of the wings of said aeroplane and connected in parallel 40 relation against said metallic structure as a counterpoise.

2. An antenna for a propelled vehicle with a metallic structure, comprising a plurality of freely trailing wires symmetrically spaced to be clear of said vehicle, and means for connecting said wires as an antenna against the said metallic structure as a counterpoise.

3. An antenna system for an aeroplane 50 having wings and a metallic structure, comprising a pair of trailing wires attached near the extremities of said wings and connected together as an antenna against said structure as a counterpoise.

4. A traveling electrical radiating system comprising a vehicle having a transverse portion and a metallic framework, a plurality of trailing conductors attached to said transverse portions at points symmetrically 60 disposed with respect to said vehicle, and means for connecting said conductors in parallel as an antenna against said metallic framework as a counterpoise.

5. A traveling electrical radiating system 65 comprising a vehicle having a transverse portion and a metallic framework, a plurality of trailing conductors attached to the extremities of said transverse portion, and means for connecting said conductors in parallel as an antenna against said metallic framework as a counterpoise.

In witness whereof, I hereunto subscribe my name this 24th day of April A. D., 1919.

ARTHUR A. OSWALD
